APPARATUS FOR GENERATING GAS

Filed Aug. 21, 1920

UNITED STATES PATENT OFFICE.

SETH HAYES, OF CLEVELAND, OHIO.

APPARATUS FOR GENERATING GAS.

Application filed August 21, 1920. Serial No. 404,988.

To all whom it may concern:

Be it known that I, SETH HAYES, a citizen of the United States, residing at Cleveland, in the county of Cuyahoga and State 5 of Ohio, have invented certain new and useful Improvements in and Relating to Apparatus for Generating Gas, of which the following is a specification.

This invention relates to an apparatus for 10 generating gas or gases, more particularly to chemical apparatus for causing reactions between materials, such for example as a compound or an elemental substance and an acid.

15 One object of the invention is to provide an apparatus of this character comprising a relatively few number of parts shaped and arranged for correlation whereby certain experiments and formulæ may be readily and easily carried out.

Another object of the invention is to provide an apparatus of this character so constructed that certain of the materials may be repeatedly used, and others readily substituted.

Other objects of the invention will be apparent to those skilled in the art to which my invention relates from the following description taken in connection with the accompanying drawing.

Referring to the drawing wherein, I have shown, and herein described, one form of apparatus embodying my invention:

Fig. 1 is a view, partly in elevation and 35 partly in section, of an apparatus embodying my invention.

Fig. 2 is a longitudinal sectional view of the apparatus.

Fig. 3 is a horizontal section on the line 40 3—3 of Fig. 2.

Fig. 4 is a section on the line 4—4 of Fig. 2.

Fig. 5 is a view in perspective of the outer liquid-holding element of the apparatus.

45 Fig. 6 is a side elevation of the bell element of the apparatus.

Fig. 7 is a perspective view of the closure for the lower, open, end of the bell.

Fig. 8 is a plan view of the supporting 50 ring for holding the bell in proper position within the liquid-holding vessel.

In the drawing, 1 indicates a cylindrical member, closed at its lower end. The member 1 is arranged to hold any desired quantity of certain of the material or materials—preferably a liquid material or ma-

terials—which is or are to be used in the generating of a gas or gases. I have shown this holder 1 as a graduate, whereby it may be conveniently used as such and as a piece 60 of apparatus capable of use in generating gas, as will be later set forth. The graduate is provided with the usual graduations or scale 1^a on one side and also an indicating line 1^b to indicate the quantity of material 65 that is to be placed therein when it is used as a generator. The upper or open end of the graduate 1 is inclined downwardly from the pouring lip 1^c to a point diametrically opposite the lip, as shown at 1^d, the purpose 70 of which inclined end will later be described.

2 indicates a bell arranged to hold other material or materials which is or are to be used in the reaction. The bell 2 is constructed so that it may telescope into the graduate 1 (see Figs. 1 and 2) to permit contact 75 of the materials placed in it and the graduate 1.

3 indicates a device fitted to the lower open end of the bell and adapted to retain 80 the material or materials placed in the bell therein and also to support the materials therein when the bell is correlated with the graduate 1 to permit a reaction and the generation of gas. The material supporting 85 device 3 preferably comprises a plug or stopper, formed of suitable chemical resisting material, and frictionally engaging the inner walls of the bell 2. At 3^a, the plug 3 is formed with a groove, through which the liquid in the graduate 1 passes or flows into the bell 2 when the latter is positioned in the graduate 1, as shown in Figs. 1 and 2.

The plug 3 may be provided with a plurality of grooves 3^a uniformly spaced around 90 its side wall. 4 indicates a delivery tube connected to the upper end of the bell 2. The tube 4 is preferably formed integral with the walls of the bell 2 and its upper end may be bent downwardly to permit the 95 easy attachment of one end of a flexible tube 5 without causing a kink in the latter. The flexible tube 5 is preferably connected at its opposite end to one end of a bent tube 6,

the free open end of which is submerged in 100 a hydraulic tank 7 so that the gas conducted by the tubes 5 and 6 from the bell 2 will rise into a receiver 8 which is inverted and supported on the shelf 7^a in the tank 7.

9 indicates the means for connecting the bell 2 to and supporting it within the graduate or holder 1 with its lower end sub-

merged to the desired extent in the liquid material therein, as shown in Fig. 2. The connecting and supporting means 9 are preferably constructed in such manner that they 5 support the bell 2 at the desired point or height, preventing it from descending downwardly, but permit it to move upwardly due to explosion of the gas, thus avoiding an explosion of the apparatus and resulting 10 damage and injury. The connecting and supporting means 9 preferably comprise a clutch ring, which, by engagement with the inclined end wall 1^c of the holder 1, is caused to clamp the opposite sides of the bell 2 and 15 thus support it in the holder 1. In order to insure a locking between the bell 2 and clutch ring, I prefer to roughen, in a well-known manner, the opposite sides of the bell 2, as shown at 10.

20 My invention is adapted for generating gas or gases for practical purposes and for conducting chemical experiments in a chemical laboratory. For these purposes a certain quantity of dry material B may be 25 placed inside the bell 2 and the stopper or plug 3 applied to its lower end. The experiment may then be carried out. As soon as the reaction is completed the bell 2 may be raised above the material in the graduate, 30 or it may be removed from the holder 1 and its lower end submerged in water or other solution to wash the material B or carry out another reaction by the substitution of another charged bell 2; the grooves 3^a permitting 35 the water or solution to flow into the bell 2 into contact with the material therein. It will thus be seen that after the bell 2 is charged with the desired materials, several chemical experiments can be carried out 40 without recharging the bell 2. Various materials may be used as desired for causing reactions, for example I may put a charge of zinc in the bell 2 and a charge of hydrochloric acid in the holder 1, and when the 45 bell 2 is positioned therein, the hydrochloric acid will flow through the grooves 3^a and permit the following reaction:

50 the hydrogen gas passing off through the tubes 4, 5 and 6 and being collected in the receiver 8.

What I claim is:

1. In apparatus of the class described, the 55 combination of a liquid holder open at its upper end, a bell telescopically fitting said

holder and arranged to collect gas in its upper portion, and a detachable device for closing the lower end of said bell and holding material therein, said device being formed with a groove through which the liquid in the holder may flow to permit reactions in said bell. 60

2. In apparatus of the class described, the combination of a graduate for liquid, a bell 65 removably fitting into said graduate, and a plug removably fitting the lower end of said bell for closing it and holding material therein, said plug being formed with an opening through which the liquid in said 70 graduate may flow into said bell.

3. In apparatus of the class described, the combination of a holder for liquid, a bell removably fitting into said holder and arranged to collect gas in its upper portion, 75 detachable perforated means for closing the lower end of said bell, whereby material may be retained therein to permit reactions due to liquid flowing through the perforation of said closing means, and means engaging said bell and the upper end of said holder for supporting said bell thereon, but permitting its movement upwardly. 80

4. In apparatus of the class described, the combination of a holder for liquid, a bell 85 removably fitting into said holder and arranged to collect gas in its upper portion, detachable perforated means for closing the lower end of said bell, whereby material may be retained therein to permit reactions 90 due to liquid flowing through the perforation of said closing means, and means adjustably engaging said bell and the upper end of said holder for supporting the bell in said holder with its lower end at any 95 height relative to the bottom of said holder.

5. In apparatus of the class described, the combination of a graduate for liquid, the upper end of said graduate being inclined from one side to the other, a bell arranged 100 to telescope into said graduate, perforated means for closing the lower end of said bell, whereby material may be retained therein to permit reactions due to liquid flowing through the perforation of said closing means, and a clutch ring engaging the upper inclined end of said graduate and the sides 105 of said bell to support the latter in said graduate.

In testimony whereof I affix my signature.

SETH HAYES.
